P. CROVO.

LIQUID VALVE.

APPLICATION FILED OCT. 7, 1915.

1,223,038.

Patented Apr. 17, 1917.

UNITED STATES PATENT OFFICE.

PAUL CROVO, OF CARLSTADT, NEW JERSEY, ASSIGNOR TO BEVERAGE MACHINE AND BOTTLE CO., INCORPORATED, OF NEW YORK, N. Y., A CORPORATION OF NEW YORK.

LIQUID-VALVE.

1,223,038.

Specification of Letters Patent. Patented Apr. 17, 1917.

Application filed October 7, 1915. Serial No. 54,635.

To all whom it may concern:

Be it known that I, PAUL CROVO, a subject of the King of Italy, residing at Carlstadt, in the county of Bergen, in the State of New Jersey, have invented certain new and useful Improvements in Liquid-Valves, of which the following is a specification, reference being had to the accompanying drawings, forming a part hereof.

10 In Letters Patent No. 1171356, dated February 8, 1916, granted to Philip J. Saulson, for filling machine, there is shown and described a machine for filling bottles, siphons and other receptacles with any liquid, 15 whether charged with gas or not, under pressure and out of contact with atmospheric air. Embodied in said machine are shown devices for introducing into each receptacle a measured quantity of syrup or extract to be mixed in the receptacle with the main body of the liquid with which it is filled. In carrying out the successive operations in said machine, there were provided two or more valves which were deemed to 20 be necessary to control, respectively, the flow of liquid into and from the measuring vessel provided therefor, the flow of syrup into and from its measuring vessel, and the introduction of gas into each of these receptacles for the purpose of forcing the liquids 25 therefrom into the siphon to be filled. The present invention has for its object to provide a liquid valve which shall be especially useful in connection with a machine of the 30 general character referred to and which shall be of such construction as to take care of the several operations referred to briefly above and insure the proper sequence of such operations under all conditions of use. 35 By means of the improved valve it becomes unnecessary to employ the several valves shown in the copending case referred to and, accordingly, the liability to damage or derangement of the filling machine is decreased to that extent and the cost thereof is 40 lessened in proportion to the number of parts eliminated. The improved valve embodies the further advantages of cheapness of cost, simplicity of construction, certainty 45 of operation, ease of assembling and disassembling, and freedom from leakage. The invention will be described in detail with reference to the accompanying drawings, in which—

Figure 1 is a view partly in side elevation and partly in section of the improved valve.

Fig. 2 is a view in transverse section taken therethrough on the plane indicated by the line 2—2 of Fig. 1 and looking in the direction of the arrows.

Fig. 3 is a view in transverse section taken through the valve shown in Fig. 1 along the plane indicated by the line 3—3 and looking in the direction of the arrows.

Fig. 4 is a fragmentary view in elevation of so much of the valve as is shown in vertical section in Fig. 1.

While particular reference has been made in the preamble to the use of the improved valve in a machine such as is illustrated in the copending application above identified, it will be understood as this description proceeds that the invention is not to be limited to the use of the valve in a machine of this identical character inasmuch as wide changes in the construction of such machine may be made without changing the mode of operation of the valve. However, it will be helpful to describe the improved valve in connection with said machine inasmuch as many of its advantages may be best illustrated in connection with a description of its operation in connection with the machine.

The improved valve *a* is generally of the plug type being of tapered form and disposed rotatably within a conical casing *b* in such manner as to be self-grinding, as will appear later. The stem *a'* of the valve extends through the end wall *b'* of the valve casing *b* and is slotted, as at *a*², to receive adjustable abutment devices to be described, for a spring *c* by which the valve is maintained in snug engagement with the inner wall of the casing. The rear wall *b'* of the casing *b* carries, or has formed integral therewith, an annular flange *b*² which receives a circular wear plate *d* on which run balls *e* which may be maintained in proper mutual relationship by a ball cage *f* of any approved form. These balls are held against the face of the wear plate *d* by means of a ring washer *g* on which seats the spring *c*. The other end of the spring *c* abuts against a ring *h* through which the stem *a'* of the valve *a* extends loosely and the ring is engaged, in turn, by a diametrically disposed block *i* which extends through the slot *a*² in

the valve stem a' and is guided thereby. The position of the block i within the slot a^2 may be determined by an adjustable thumb screw k which is disposed in the end of the valve 5 stem a' . From the description given, it will be evident that by suitable adjustment of the thumb screw k the tension of the spring c may be adjusted, thereby permitting the ready determination of the degree of friction 10 between the valve a and its casing b . By reason of the disposition of the balls e , whereby an anti-friction bearing for the end of the valve is provided, the degree of friction 15 between the circumferential face of the valve and the conical wall of the casing b is the measure of the force required to rotate the valve within the casing. The desirability of providing for the adjustment of the tension of the spring c will be evident 20 when the different conditions of use of the valve are taken into account. For instance, the greater the pressure of the fluid passing through the valve, the more necessary it is that the engagement between the valve and 25 the valve casing be absolutely tight.

As brought out clearly in Figs. 2 and 3 the improved valve is provided with two separate sets of passages therein and the valve casing has two separate sets of liquid pipes 30 communicating therewith and adapted to be placed in communication with one another, respectively, by the said passages, through proper manipulation of the valve. To illustrate, it may be supposed that the valve is 35 to be used in a filling machine of the type described in the copending case referred to. In this machine, there is, roughly speaking, a carbonated water supply, a measuring tank for this water, a main syrup tank, a measuring 40 tank for the syrup, a main gas supply and the bottle to be filled. In the operation of this machine, a predetermined quantity of carbonated water flows from the water supply into the measuring tank at the same time 45 that the syrup in the syrup measuring tank flows into the bottle. The inflow of water into its measuring tank displaces gas within the tank and forces it into the syrup measuring tank where it does useful work in forcing 50 the syrup into the bottle. The syrup having been introduced into the bottle and the appropriate quantity of water having been permitted to flow into the water measuring tank, it becomes necessary to change 55 the connections so that the predetermined quantity of water will flow into the bottle under pressure of gas, and the empty measuring tank for the syrup will be replenished. During these operations, the main gas supply 60 is connected directly to the measuring tank of the water and the measuring tank for syrup is disconnected from the bottle. The operations outlined herein have heretofore been controlled by two or more 65 valves, each one of which has been adapted

to control only one or perhaps two of the operations. The improved valve is of such construction as to enable it to perform all of the functions of the several valves heretofore employed and permit it to have connected therewith the several liquid and gas pipes by which the several fluids are conducted, in proper sequence, to the intended receptacles therefor. From Figs. 1 and 2 it will be seen that the valve casing b has 70 formed adjacent to one end a circumferential series of ports b^3 , b^4 , b^5 , b^6 and b^7 with which communicate pipes l , l' , l^2 , l^3 and l^4 which lead to the carbonated water supply, the syrup tank, the syrup measuring device, 80 the bottle and the water measuring device respectively. The ports referred to, five in number, are preferably placed at equidistant points along the circumference of the valve casing b , making them, in the illustrated embodiment, about 72° apart. The valve a has two channels a^3 and a^4 formed therein, the legs of which subtend angles of about 72° each on the circumference of the valve to 85 permit the ends of such passages to be 90 brought into registration with adjacent ports of the valve casing, as appears clearly in Fig. 2.

Adjacent the other end of the valve casing is formed a circumferential series of ports 95 b^8 , b^9 and b^{10} which communicate with pipes l^5 , l^6 and l^7 , which are connected to the main gas supply, the gas connection to the water measuring device and the gas connection to the syrup measuring device respectively. 100 These three ports are preferably placed about the circumference of the valve a 72° from one another, when measured in one direction. The valve a is provided at this end with a single passage a^5 , the ends of which may be 105 brought into registry with the ports b^8 and b^9 or with the ports b^9 and b^{10} . The valve a may be rotated in its housing by means of a handle m fixed on a stem a^6 which extends 110 from the end of the valve. In the improved 115 machine shown in the copending case referred to, rotation of the valve may be controlled automatically, but for the purpose of this description it will be sufficient to assume that the valve is manipulated manually. In operation, assuming that the water measuring tank is filled and that the syrup from the syrup measuring tank has been 120 emptied into the bottle, the valve may be rotated to the position shown in Figs. 2 and 3 in which the water measuring device is placed in communication with the bottle through the passage a^4 in the valve. When in this position, the passage a^3 in the valve a spans the ports b^4 and b^5 so that syrup may 125 flow from the syrup tank to the syrup measuring device. The third passage a^5 in the valve is, at the same time, in communication with the ports b^8 and b^9 so as to establish 130 communication between the main gas supply 135

⁷⁵ and the gas connection to the water measuring device ⁷⁶. At this time the carbonated water supply is cut off as is the gas connection to the syrup measuring device. When ⁵ the valve is moved counter clockwise through an angle of about 72° the carbonated water supply ⁷ will be placed in communication with the water measuring device through the valve passage ^{a⁴} so that the water is permitted to run into the measuring tank. Simultaneously, the syrup is permitted to run from the syrup measuring tank into the bottle, through the valve passage ^{a³}. The water flowing into the measuring tank then ¹⁵ forces the gas from the tank into the top of the syrup measuring tank through the valve passage ^{a⁵} which spans the ports ^{b⁹} and ^{b¹⁰}. The gas flowing into the syrup measuring tank serves to force the syrup therefrom into ²⁰ the bottle.

The improved valve as described not only fulfills all of the functions heretofore derived from the use of two or more valves and permits a single and simultaneous control of the ²⁵ various operations, thereby insuring the desired sequence thereof, but possesses many structural advantages as regards the cost, simplicity, etc. For instance, the valve shown in Fig. 1 may be readily removed ³⁰ from its housing by slipping the block ⁱ out of engagement with the abutment ring ^h and then withdrawing the valve axially from the housing. At this time the spring ^c and the associated parts are also withdrawn. The ³⁵ replacement of the valve and positioning of the elements is effected with equal facility. The conical form of the valve with the constant axial pressure exerted thereon by the spring insures a tight union between the ⁴⁰ valve and the valve casing and further results in a constant self-grinding during rotation.

The scope of the invention is pointed out more particularly in the appended claims.

⁴⁵ I claim as my invention:

1. A liquid valve comprising a casing, a plug mounted rotatably therein, a series of five ports spaced along the circumference of the casing, two passages formed in the plug ⁵⁰ to register with pairs of the ports, respectively, an independent series of three ports formed at another part of the circumference of the casing, and a separate single passage formed in the plug to register with pairs of ⁵⁵ these last named ports, respectively, whereby upon rotation of the plug four of the first named ports and two of the last named ports are placed in communication, as required.

2. A liquid valve for use in a machine for ⁶⁰ filling bottles with liquid under pressure, comprising a casing, a plug mounted rotatably therein, a series of five ports spaced along the circumference of the casing and communicating respectively with a water

supply, a water measuring device, a syrup supply, a syrup measuring device and the bottle to be filled, two passages formed in the plug to register with pairs of the ports, respectively, an independent series of three ports formed at another part of the circumference of the casing and communicating, respectively, with the main gas supply, the gas connection to the water measuring device and the gas connection to the syrup measuring device, and a separate single passage formed in the plug to register with pairs of these last named ports, respectively, whereby the plug in two positions only controls all of the operations for filling.

3. A liquid valve comprising a tapered ⁸⁰ casing, a conical plug mounted rotatably therein, a series of five ports spaced at equidistant points along the circumference of the casing 72° from one another, two curved ⁸⁵ passages formed in the plug, each of which subtends a worm of 72° and both of which are adapted to register with pairs of ports, respectively, an independent series of three ports formed at another part of the circumference of the casing at points 72° apart, ⁹⁰ measured in one direction, and a separate single curved passage formed in the plug and subtending a worm of 72° and adapted to register with pairs of the last named ports, respectively, whereby when the valve is in ⁹⁵ one position, four of the first named ports and two of the last named ports are placed in communication, and when the valve is rotated through an angle of 72° , four other of the first named ports and two other of the ¹⁰⁰ last named ports are placed in communication.

4. A liquid valve comprising a tapered casing, a conical plug, a valve stem extending through the end wall of the casing and ¹⁰⁵ slotted, a spring engaging the stem operatively to hold the plug snugly within the casing and an adjustable abutment for the spring disposed in the slot and guided thereby.

5. A liquid valve comprising a tapered casing having an end wall, a conical plug mounted rotatably within the casing, a valve stem extending through the end wall of the casing and slotted, a spring operatively interposed between the end wall of the casing and the valve stem to maintain the plug in snug engagement with the casing, an abutment for the spring disposed in the slot and guided thereby and a thumb screw in the end ¹¹⁵ of the valve stem and extending into the slot to afford an adjustable seat for the spring abutment.

6. A liquid valve comprising a tapered casing, a conical plug mounted rotatably ¹²⁵ therein, a valve stem extending through the end wall of the casing and slotted, an annular flange carried by the end wall of the

21
casing, a ball race disposed loosely within the annular flange and provided with an opening through which the valve stem extends, a ball bearing resting against the ball race, 5 a ring washer engaged by the ball bearing on the other side, a spring seated on the ring washer, an abutment for the spring comprising a block disposed in the slot and guided

thereby, and a thumb screw threaded into the end of the valve stem and engaging the 10 abutment block to permit the adjustment of the tension of the spring, all of said parts being removable.

This specification signed this 30th day of Sept. A. D. 1915.

PAUL CROVO.
